Patented Jan. 9, 1973

225,813

STUDY CARREL

Frank R. Torrey, 9805 Dallas Ave.,
Silver Spring, Md. 20901

Filed Feb. 19, 1971, Ser. No. 117,196

Term of patent 14 years

Int. Cl. D6—04

U.S. Cl. D6—189

FIG. 1

FIG. 3

FIG. 2

FIG. 1 is a perspective view of a study carrel, showing my new design;

FIG. 2 is a rear elevational view thereof, and

FIG. 3 is a right side elevational view thereof, the left side being a mirror image thereof.

I claim:

The ornamental design for a study carrel, as shown and described.
